United States Patent Office.

HENRY KASSING, OF NEW YORK, N. Y.

Letters Patent No. 74,830, dated February 25, 1868.

IMPROVEMENT IN MACHINES FOR CUTTING VENEERS.

The Schedule referred to in these Letters Patent and making part of the same.

TO ALL WHOM IT MAY CONCERN:

Be it known that I, HENRY KASSING, of the city, county, and State of New York, have invented a new and improved Machine for Cutting Veneers, and that the following description, taken in connection with the accompanying drawings, hereinafter referred to, forms a full and exact specification of the same, wherein I have set forth the nature and principles of my said improvements by which my invention may be distinguished from all others of a similar class, together with such parts as I claim, and desire to have secured to me by Letters Patent.

This invention relates to a new and improved machine for cutting veneers, and consists in the employment or use of a reciprocating knife, arranged to work in a plane slightly inclined from a vertical position, in connection with a laterally-moving log-carriage; all being combined and arranged in such a manner that the knife is made to operate with a drawing cut, and perform its work in a perfect manner and with but a moderate expenditure of power. In the accompanying sheet of drawings—

Figure 1 is a front view of my invention,

Figure 2 a transverse vertical section of the same, taken in the line *x x*, fig. 1.

Similar letters of reference indicate like parts.

A represents the frame of the machine, which may be constructed in any proper manner to support the working parts. This frame has two guides, *a a*, attached to it at each side of its top or upper part, and between these guides, slides *B* are fitted, and allowed to move freely up and down, the knife-stock *B'* being secured between the slides. The guides *a a* are slightly inclined from a vertical plane, as shown clearly in fig. 2, and the slides *B* of the knife-stock are connected by rods *b* with crank-pulleys *c c*, on a driving-shaft, *C*, in the lower part of the frame *A*. *D* represents a knife, attached to the stock *B'*, and *E* is an adjustable gauge, fitted on a bar, *F*, the ends of which are attached to the slides *B*. So far as the construction and arrangement of the knife-stock and gauge are concerned, there is nothing essentially new, but the inclination of the guides *a a* is new, and attended with an important result, as will be hereinafter mentioned. *G* is a bar, to which the log or bolt from which the veneers are cut is attached. This bar *G* is attached to a carriage, *H*, which is placed on the top of the frame *A*, and arranged in such a manner that it may move freely thereon in a lateral direction. The carriage may be thus moved or operated by means of straps *I I*, attached to the under side of the carriage, and passing over pulleys *J J*, and connected to levers *K K*, one at each side of the lower part of the frame *A*, said levers being acted upon by cams *L L*, on the driving-shaft *C*, which cams are placed in a reverse position on the shaft, so that the straps *I I* will be actuated or drawn down alternately, in order to give a reciprocating movement to the carriage *H*. The bar *G*, to which the log is attached, is fitted on ways or guides *d d*, on the carriage *H*, and is adjusted by means of the worm-shaft *M*, the screws *M'*, and worm-wheels *N*. The length of the movement of the carriage *H* should be about equal to the length of the movement of the knife, and it will be seen that owing to the longitudinal movement given to the log or bolt, while the knife *D* is cutting a veneer from it, a drawing cut is virtually obtained, and the knife made to perform its work smoothly, and with but a moderate expenditure of power. When the knife *D* is drawn down, the connecting-rods *b* draw and keep the slides *B* in contact with the rear guides *a*, and prevent any unnecessary lateral play of the slides between the guides. The inclination of the guides *a a* admits of this result being perfectly attained, to wit, a pressure of the slides *B* against the rear guides during the descent and working movement of the knife, whereby the latter is made to cut with a firm, unwavering stroke, which insures smooth and even work being done.

Having thus described my invention, I claim as new, and desire to secure by Letters Patent—

The worm-shaft *M*, worm-wheels *N*, screws *M'*, and bar *G*, upon the inclined guide *d*, all constructed, arranged, and operating upon the laterally-moving table *H*, as herein described for the purpose specified.

HENRY KASSING.
